Primary Examiner — Ian F Whitmore(57) **CLAIM**

The ornamental design for a display screen or portion thereof with a graphical user interface, as shown and described.

DESCRIPTION

FIG. 1 is a front view of a first embodiment of a display screen or portion thereof with a graphical user interface, showing my new design; and, FIG. 2 is a front view of a second embodiment of a display screen or portion thereof with a graphical user interface. The broken lines in the drawings illustrate a mobile phone with a display screen and form no part of the claimed design.
